RECEPTACLE

James E. Cheneweth, National City, Calif.

Application March 16, 1953, Serial No. 24,051

Term of patent 14 years

(Cl. D44—1)

To all whom it may concern:

Be it known that I, James E. Cheneweth, a citizen of the United States, residing at National City, State of California, have invented a new, original, and ornamental Design for a Receptacle, of which the following is a specification, reference being had to the accompanying drawing, forming a part hereof.

This application is a continuation-in-part of design application for a Receptacle, Serial No. D. 22,208, filed November 8, 1952.

Fig. 1 is a top perspective view of the receptacle showing my new design.

Fig. 2 is a bottom perspective view thereof.

The dominant features of my new design are shown in solid lines in the drawing, the broken line showing of a handle being omitted from Figure 2 for convenience of illustration.

The drawing figures are stippled to indicate visual contrast.

I claim:

The ornamental design for a receptacle, as shown.

JAMES E. CHENEWETH.
